UNITED STATES PATENT OFFICE.

AARON B. COOLEY, OF PHILADELPHIA, PENNSYLVANIA.

IMPROVEMENT IN ADJUSTABLE REVERSIBLE PROPELLERS.

Specification forming part of Letters Patent No. 35,219, dated May 18, 1862.

To all whom it may concern:

Be it known that I, AARON B. COOLEY, of Philadelphia, Pennsylvania, have invented an Improvement in Adjustable Propellers; and I do hereby declare the following to be a full, clear, and exact description of the same, reference being had to the accompanying drawings, and to the letters of reference marked thereon.

My invention consists of a screw-propeller constructed and operating as described hereinafter, so that the blades may be reversed, thereby rendering the propeller a portion of a left-handed or a portion of a right-handed screw at pleasure, without interfering with the motion of the propeller-shaft.

In order to enable others to make and use my invention, I will now proceed to describe its construction and operation.

On reference to the accompanying drawings, which form a part of this specification, Figure 1 is a side view of my improved adjustable and reversible propeller; Fig. 2, an end view, partly in section; and Fig. 3, a sectional view.

Similar letters refer to similar parts throughout the several views.

The line A represents the outside of the stern-post of the vessel, to which is secured the bearing B for the projecting end of the propeller-shaft C.

D is a hollow cylindrical casing with a rounded outer end, and in the interior of this casing and forming part of the same is the annular projection d, to which the projecting end of the propeller-shaft C is firmly secured. From the inside of the casing and near the rounded end of the same projects the two hubs e and e', one being situated directly opposite the other, and into the hub e the stem h of the blade H fits snugly, but so as to turn freely, the stem h' of the blade H' fitting into the opposite hub, e'. Each blade consists of a simple flat plate of cast-iron, malleable iron, or brass, the stem either forming a part of or being firmly secured to the plate.

To the stem h of the blade H is secured an arm, G, and to the stem h' of the blade H' is secured a similar arm, G', the latter being connected to a projection, i, on the ring F by a link, E, while the arm G is connected by a link, E', to a projection, i', on the same ring,

F. This ring F fits snugly, but so as to slide freely on the outside of the casing, in which, as well as in the annular projection d, are formed openings for the free movement of the projections i and i' and links E and E'.

On the outside of the ring F is cut a recess for the reception of the ring J, which is made of two pieces bolted together at j and connected by the two links M and M' to the forked end of the lever N, which has its fulcrum on a pin passing through a bracket, u, secured to the stern-post or to the stationary bearing B.

The casing D, two blades H and H', arms G and G', links E and E', and the ring F, with its projections, revolve with the propeller-shaft C, while the ring J has no other movement than that which may be imparted to it by means of the forked lever N.

When the ring F has been pushed to the limit of its movement in the direction of the arrow, the blade H will have assumed the position illustrated by the line x, and the blade h' the position shown by the line y. When the ring F, however, has been moved to its full extent in the direction contrary to that pointed out by the arrow, the blade represented by the line x will assume the position shown by the line y and the latter the position shown by the line x. It will thus be seen that by the movement of the lever N the direction of the blades may be instantly reversed, so as to convert the propeller formed by the blades from a right-handed to a left-handed screw, thereby allowing the attendant to change the direction of the vessel without interfering with the continuous rotation of the propeller-shaft in one direction.

My invention is especially applicable to propeller vessels of smaller size—such as are used on canals—as it obviates the necessity of close attendance to the revolving gear of the engine.

Another important object of my invention is the facility with which the blades of the propeller can be adjusted so as to present a coarser or finer threaded screw at pleasure, which adjustment will depend upon the judgment of the attendant, who will be guided by the increased or diminished loading of the vessel and the extent of duty to be accomplished by the engine and propeller.

Although I have shown the ring F as ar-

ranged for being operated by a lever, N, it will be evident that it may be moved backward and forward over the casing D by racks and pinions and other appliances which will readily suggest themselves to experienced engineers.

I wish it to be understood that I do not desire to claim, broadly, a propeller the blades of which can be adjusted to different angles; but

I claim as my invention and as an improvement in that class of propellers—

The blades H and H', arms G and G', links

E and E', the sliding ring F, and ring J, when the whole of the above parts are arranged on the hollow hub or casing D for joint action, as set forth, and when the said ring J is operated by the links M and M' and lever N, or their equivalents, as specified.

In testimony whereof I have signed my name to this specification in the presence of two subscribing witnesses.

AARON B. COOLEY.
